UNITED STATES PATENT OFFICE

90,796

DESIGN FOR A TRANSPORT AEROPLANE

Robert W. Ayer, Wayne, Mich., assignor to
Stinson Aircraft Corporation, Wayne, Mich.,
a corporation of Michigan

Application April 17, 1933. Serial No. 47,818

Term of patent 7 years

To all whom it may concern:

Be it known that I, ROBERT W. AYER, a citizen of the United States, residing at Wayne, in the county of Wayne and State of Michigan, have invented a new, original, and ornamental Design for Transport Aeroplanes, of which the following is a specification, reference being had to the accompanying drawings forming a part thereof.

Figure 1 of the drawings is a plan view of a transport aeroplane embodying the new design;

Figure 2 is a front elevation, the landing gear

of the aeroplane being shown in its flying or collapsed position;

Figure 3 is a side elevation, the landing gear of the aeroplane being shown in its ground position; and

Figure 4 is a perspective view of the aeroplane.

I claim:

The ornamental design for a transport aeroplane substantially as shown.

Wayne, Michigan, March 17, 1933.

ROBERT W. AYER.
